United States Patent Office.

JOHN A. THOMPSON, OF AUBURN, NEW YORK, ASSIGNOR TO HIMSELF AND
LORENZO W. NYE, OF SAME PLACE.

Letters Patent No. 75,709, dated March 17, 1868.

IMPROVEMENT IN MACHINE FOR GRINDING KNIVES OF HARVESTERS.

The Schedule referred to in these Letters Patent and making part of the same.

Be it known that I, JOHN A. THOMPSON, of the city of Auburn, in the county of Cayuga, and State of New York, have invented a new and useful Improvement on a Grinding-Machine; and I do hereby declare that the following is a clear, full, and exact description of the construction and operation of the same, reference being had to the annexed drawings, making a part of this specification, in which—

Figure 1 is a perspective view.

Figure 2 is a sectional view of the pedestal and base.

Figure 3 is a view of a reaper-section and protective hood.

Figure 4 is a section of stone, shaft, crank, and its bearings.

Figure 5, a section of shaft, crank, and spring-key.

Figure 6 is a transverse section of rest, section-bar, and hood.

Figure 7 is a similar section, to show a rotary guard, and its attachment to the bar-support, and its rotation on the side of the stone.

A, grindstone, which should be dressed true on its face and sides, at a right angle with the face; B, shaft; C, crank; D, bearing; E, frame; F, base; G, pedestal; H H, elastic clamps; I, supporting-bar; J J J J, toggle-joints; K, bar for support of sections, or articles to be ground; L, reaper-bar and sections; M, hood or guard; N, rotary guide-guard; O, thimble or socket of metal; P, urn-support or stand; Q, urn; R, water-guides; S, water-basins; T, bolts and thumb-screw; U, slot; V, lugs.

To grind truly and properly, the set of sections or shear-blades of a reaping or mowing-machine requires that they should move in definite lines upon the stone while being ground. To accomplish this requires that the machine be so constructed that its movements and operations shall be subject to the control of the operator. On this account the bank of "sections" is presented to demonstrate the exact operations of the various parts of the machine.

I propose to construct the frame of this machine of angle-iron, or of wood in same form, in order to secure greater firmness and safety in transporting. The frame E is firmly riveted together at its angles, and the thimble O is riveted in position, in the corner, to the rail and cross-tie. The leg being turned to fit this socket, is readily held by wood-screw passing through thimble into leg. P, a support for the water-urn; this may be held firm to frame by means of bolt or socket. The urn Q should be furnished with a faucet, so as to regulate the supply of water, to keep the stone on face or side clean. This water flowing from the stone is conveyed by the conductors or guides R from the stone into water-basin S.

I construct the foot or base, F, of the pedestal of firm, hard wood, provided with a slot, as shown in fig. 2 at U, through which the bolt T passes into the plank-tie in frame, by which means it may be moved from or towards the stone, or be rotated from side to side of the stone, and held firm in any desired position by bringing down the thumb-screw. A small bolt or rivet should be passed through the ends of the base, to prevent the slot splitting out. I attach, by two screws or by bolt, two strips of band-iron, or other suitable material, to form the sides of elbow-joint connection with the pedestal G, the lower end of which is rounded from its back forward, as shown in section, fig. 2. The upper end of the pedestal is rounded from side to side, which allows the supporting-bar I to be tilted or tipped at any angle. The sides of this connection are also of wrought metal, elastic, so the bar can be rotated or held firm by the screw and bolt. I attach to the supporting-bar I the lower ends of the toggle-joints J, which should be made of cold-drawn iron or steel, in order to be light and firm. These are connected by thumb-screws, so as to be held firm, or moved, as desired.

The bar K, for supporting the "sections" or articles to be ground, is ploughed in L-form, or made of angle-iron, through which bolts with lug-ends are passed, and held firm against the section-bar and the L-bar. The section-bar can slide or be moved readily on this way and the lugs.

The hood or guard M should be constructed from copper, brass, or such metal as will not injure the edge of the knife or section, and in angle or such form as will fit upon the section, and may be held by clamping the lower edge of the section, or by a pin, as represented in section, fig. 3. Fig. 7 shows a guard, with a roller mounted in a frame made of wrought metal or malleable metal, attached, by lug and thumb-screw, to cutter-bar

and its support, which is placed so as to protect the knife or section from coming in contact with the stone to its injury, the roller moving readily upon the sides or face of the stone. This guide-roll may be made of rubber, iron, wood, or other suitable material.

The shaft B is so made as to receive the crank C readily upon either end, so it may be shifted from side to side, out of the way of the sections, as required. The crank may be attached to shaft, by means of a spring-key or nut.

The operation of this machine is seen clearly in draught. The bar of sections is placed on the way-lugs, and the knife to be ground brought in contact with the stone, commencing grinding at its lower angle, the bevel lying true upon the stone, which is readily accomplished by a turn of screw-holding base; move this up or back from stone or to side, and then fasten by turning nut at base of the pedestal, and carry the sections to the stone; turn upon nut, and tilt the supporting-bar to right point, so as to place all as desired, and fasten firmly now by means of toggle-joints. The upper bar may be depressed, or may be carried to right or left, so as to cause the knife to move in all required lines upon the face or sides of the stone, so with ordinary care and skill a proper edge can be secured.

Claims.

What I claim, and desire to secure by Letters Patent, is—

1. In combination with the movable base F, pedestal G, and tilting supporting-bar I, the elastic clamps H H, with thumb-screw and bolt T, forming movable joints, for the purposes set forth.
2. The connection of the supporting-bar I, by the toggle or elbow-joints J J J J, with bar K.
3. The hood-guard M and the rotary guard N, as and for purposes specified.
4. The thimble O and angular frame E, all combined and operating in manner substantially as set forth, and for the purposes specified.

In testimony that I claim the foregoing, I hereunto affix my signature, in presence of—

JOHN A. THOMPSON.
